UNITED STATES PATENT OFFICE.

OGDEN P. LETCHWORTH, OF BUFFALO, NEW YORK.

DESIGN FOR A SNAP-HOOK.

SPECIFICATION forming part of Design No. 17,975, dated December 20, 1887.
Application filed May 18, 1887. Serial No. 238,704. Term of patent 7 years.

To all whom it may concern:

Be it known that I, OGDEN P. LETCHWORTH, of the city of Buffalo, in the county of Erie and State of New York, have invented a new and original Design for Snap-Hooks, of which

5 the following is a specification.

This invention relates to a novel design for a snap-hook; and it consists of the design, which will be hereinafter described and claimed, and

10 which is represented in the accompanying drawings.

The leading feature of my design consists of a raised rib or bead extending longitudinally along the bottom and end portions of the body

15 of the hook.

In the accompanying drawings, Figure 1 is a side elevation of the snap-hook. Fig. 2 is a top plan view of the same. Fig. 3 is a cross-section in line x x, Fig. 1.

20 Like letters of reference refer to like parts in the several figures.

A represents the body of the snap-hook, composed of an inwardly-curved bottom portion, b, and upwardly and inwardly curved end portions, c c, forming continuations of the

25 bottom portion, b. The inner faces or sides of

the bottom portion, b, and end portions, c c, are made slightly convex in cross-section, as shown in the drawings, and the outer sides or faces of the bottom portion and end portions 30 are provided with a central rib or bead, d, which extends lengthwise along the bottom and end portions, and terminates near the extremities of the end portions. e represents the spring, which extends across the top of 35 the hook from one end portion to the other.

I claim as my invention—

The design for a snap-hook, consisting of the inwardly-curved bottom portion, b, and upwardly and inwardly curved end portions, c c, 40 having their outer faces provided with a central rib or bead, d, extending lengthwise along the bottom and end portions of the body of the hook, substantially as herein shown and described.

Witness my hand this 15th day of April, 45
1887.

OGDEN P. LETCHWORTH.
